United States Patent Office

Des. 226,025
Patented Jan. 16, 1973

226,025

TEST SCORING TEMPLATE OR SIMILAR ARTICLE

Carlton M. Singleton, Arlington, Va., assignor to
Automata Corporation, Richland, Wash.

Filed June 10, 1971, Ser. No. 152,007

Term of patent 14 years

Int. Cl. D10—05

U.S. Cl. D52—6

FIG. 1

FIG. 2

FIG. 1 is a top plan view of a test scoring template or similar article showing my new design;

FIG. 2 is a cross-sectional view taken on line 2—2 of FIG. 1, and

FIG. 3 is a cross-sectional view taken on line 3—3 of FIG. 1.

I claim:

The ornamental design for a test scoring template or similar article, as shown and described.
